UNITED STATES PATENT OFFICE.

ALEXANDER MCLEAN NICOLSON, OF NEW YORK, N. Y., ASSIGNOR TO WESTERN ELECTRIC COMPANY, INCORPORATED, OF NEW YORK, N. Y., A CORPORATION OF NEW YORK.

ELECTRIC-WAVE-REPEATING APPARATUS.

1,307,511.

Specification of Letters Patent. Patented June 24, 1919.

Application filed October 26, 1916. Serial No. 127,916.

To all whom it may concern:

Be it known that I, ALEXANDER MCLEAN NICOLSON, a subject of the King of Great Britain, residing at New York, in the county 5 of New York and State of New York, have invented certain new and useful Improvements in Electric-Wave-Repeating Apparatus, of which the following is a full, clear, concise, and exact description.

- 10 This invention relates to electric wave repeating apparatus, and particularly to the use of vacuum discharge repeaters, as exemplified by the so-called audion, for repeating and amplifying in an output circuit 15 waves of electric energy received in an input circuit. An object is to improve the quality of transmission by producing, in the output circuit, electric waves free from distortion with respect to the input waves.
- 20 This invention is especially useful in telephone and telegraph systems for repeating and amplifying alternating current waves of small magnitude.

The principal parts of an audion element 25 or structure are a heated filament or other source of electrons, an anode usually called a plate, and an electrode preferably located intermediate between the filament and the plate, said electrode being usually called a 30 grid. These are preferably included in an evacuated vessel. The characteristic features of the audion are that current can flow in one direction only in the space current stream, and that the strength of the current 35 in the stream flowing from its source to the plate is modified by electrostatic rather than by electromagnetic force.

A simple arrangement for using a single audion element as a repeater is as follows: 40 The input circuit has one terminal connected to the filament and the other to the grid, while the output circuit has one terminal connected to the filament and the other to the plate. Repeating coils are preferably employed in the input and output circuits respectively, and a battery is included in the output circuit in series with the primary winding of the output repeating coil. The audion repeater as thus used, 45 although a powerful amplifying agent, does not give in the output circuit a perfect reproduction of the electric waves received in the input circuit. This is due to the fact that the relation between the plate current 50 and the grid voltage is not expressed by a

straight line, and a negative charge on the grid will not produce an effect of the same magnitude as that produced by an equal positive charge.

This unsymmetrical action results in a 60 certain amount of distortion in the output waves which is avoided in accordance with this invention by employing two audion elements in a manner somewhat analogous to that shown in patent to Colpitts, 1,128,292, 65 Feb. 16, 1915 and patent to Arnold, 1,128,279, Feb. 15, 1915.

This invention will be more clearly understood by reference to the accompanying drawing, in which Figure 1 shows a perspective view of the device of this invention with certain parts broken away, and Fig. 2 illustrates diagrammatically how such a device may be employed in a circuit amplifying telephonic currents.

In Fig. 1, 3 is an evacuated vessel within which are two audion elements mounted in a suitable manner, consisting of the anode or plate members 4 and 5, the two cathodes 6 and 7, and an input electrode or grid 8, 70 common to both audion elements.

In Fig. 2, the structure of Fig. 1 is shown properly connected to an electric system for the amplification of oscillations, as previously mentioned. In order to avoid distortion, the apparatus has a divided input circuit and a divided output circuit. One arm of the input circuit comprises the cathode 6, the grid 8, battery 13 and a portion 14 of the secondary winding of the input transformer 15, the primary 16 of which receives 80 the oscillations to be amplified. The other arm of the input circuit comprises the cathode 7, the portion 17 of the secondary winding of transformer 15, the battery 13 and 85 the common grid 8. Cathode 6 is also connected through the primary winding 19 of the output transformer 20, and through battery 21 to the anode 4. Similarly, cathode 90 7 is connected through primary winding 22 and battery 23 to anode 5. Windings 19 and 22 are differentially related to the secondary 95 24, so that the resultant effect of equal currents in coils 19 and 22 is zero in coil 24. The cathodes or filaments 6 and 7 are heated 100 by the batteries 11 and 12, respectively, and then become thermionically active, thereby causing the space current to flow to their respective anodes. Batteries 21, 23 are, of 105 course, so poled as to make anodes 4 and 5 110

positive with respect to their corresponding cathodes 6 and 7, and are preferably of the same magnitude. An adjustable contact 18 is provided so that the grid 8 may be at a point of mid-input potential between the two cathodes by varying the ratio of turns in the two coils 14 and 17.

In considering the operation of the device, it is known that raising the potential of a charged body, located near a heated cathode, in general serves to increase the space current between the cathode and anode maintained positive thereto, and conversely, that lowering the potential of a charged body will in general decrease the space current. Suppose, for example, that at a given instant of time the character of the signal wave impressed on coils 17 and 14 from primary coil 16 is such as to increase the potential of filament 7; if such is the case, the potential of filament 6 will decrease. The grid 8 then will be lowered in potential with respect to the filament 7, but raised in potential with respect to the filament 6. Consequently, the thermionic current to the plate 5 from the cathode 7 will be decreased by the presence of the grid 8. Similarly, the thermionic current from filament 6 to plate 4 will be increased by the presence of the grid 8. Hence, in the output circuit containing the coil 22, there will be a decrease in current, and in the output circuit containing the coil 19 there will be an increase in the current. When the character of the signal wave at a given instant is such as to make filament 7 at a lower potential than filament 6, by similar reasoning, there will be an increase in the current through coil 22 and a decrease through coil 19. These current changes are additive in their effect on secondary winding 24. Hence, it follows that an amplified current results in coil 24 having the same frequency and wave form as the currents initially impressed on winding 16.

It is to be understood that the elimination of distortion in the repeating of current waves is not the only use to which the novel form of the evacuated vessel may be put. As an example of another use, it is apparent that if the vessel is connected up in a circuit in which one of the coils 19 or 22 is reversed, the tube may operate as a rectifier of alternating current.

55 What is claimed is:

1. An evacuated vessel containing a plurality of space current paths having electrodes individual to each of said paths, and a controlling electrode common to said paths.

2. In an electric wave repeating apparatus, an evacuated vessel containing a plurality of filaments, output electrodes individual to said filaments, and an input electrode common to said filaments.

3. In an electric wave repeating apparatus, an evacuated vessel having a plurality of audion elements comprising two anodes and their corresponding filaments located between said anodes, and a grid between said filaments. 70

4. In an electric wave repeating apparatus, the combination of two repeating elements each comprising a filament, an anode, a space current stream between said electrodes and controlling means for said space current streams, an input repeating coil the secondary winding of which is connected at an intermediate point to said controlling means and at its opposite terminals 80 to said filaments respectively. 75

5. In an electric wave repeating apparatus, the combination of an evacuated vessel containing two cathodes and two anodes, and a grid common to said elements, an input repeating coil having its secondary winding divided, said common grid being connected to an intermediate point of said divided secondary winding and the ends of said secondary winding being connected to 90 said cathodes respectively, an output repeating coil having two primary windings oppositely connected, each in series with one of said cathodes and its corresponding anode. 85

6. In an energy translating device, an evacuated vessel comprising two filaments, two anodes and a grid common to said elements, an input repeating coil having its secondary winding divided, said common grid being connected to an intermediate point of said divided secondary winding and the ends of said secondary winding being connected to 100 said filaments respectively, a divided output repeating coil having two primary windings oppositely connected, a battery for each portion of said output circuit, each primary winding being connected in series with one of said batteries, one of said filaments and its corresponding anode. 105

7. An evacuated vessel containing a plurality of space current paths each comprising a cathode, and an auxiliary electrode individual to each of said paths, and a controlling electrode common to said paths. 110

8. An evacuated vessel containing a plurality of space current paths having electrodes individual to each of said paths, and a controlling electrode separating said paths. 115

9. In an electric wave repeating apparatus, means for repeating an alternating current wave without distortion comprising an evacuated vessel containing two anodes and their corresponding cathodes located between said anodes and a grid between said 120 cathodes. 125

10. In an electric wave repeating apparatus, means for repeating an alternating current wave without distortion comprising an evacuated vessel containing a plurality of 130

space current paths having electrodes individual to each of said paths and a variable potential cold control electrode common to said paths.

5 11. In an electric wave repeating apparatus, means for repeating an alternating current wave without distortion comprising an evacuated vessel containing a plurality of space current paths having electrodes individual to each of said paths and a controlling electrode separating said paths.

10 12. In an electric wave repeating apparatus, the combination of two repeating elements, each comprising a cathode, an anode, with means for establishing a space current stream between said electrodes, a controlling means for said space current streams, and an impedance, said cathodes being connected to the terminals of said impedance and said 15 20 controlling means being connected to an intermediate point of said impedance.

13. An electric wave repeating apparatus comprising divided input and divided output circuits, means for producing two space 25 current paths, said paths being oppositely included in said output circuit, and a variable potential cold control electrode common to said paths.

14. In an electric wave repeating apparatus, the combination of two repeating elements comprising an input electrode, a cathode and an anode for each said element, an input repeating coil the secondary wind-

ing of which is connected at an intermediate point to said input electrode and its opposite 35 terminals to said cathodes respectively.

15. In an electric wave repeating apparatus, the combination of two repeating elements comprising an anode and a cathode for each said element, an input electrode 40 common to said elements, an input repeating coil, an output repeating coil, the terminals of the secondary winding of said input repeating coil being connected to said cathodes respectively and the primary winding of 45 said output repeating coil being divided and the divisions connected to said repeating elements respectively.

16. In an electric wave repeating apparatus, the combination with input and output 50 circuits and a repeating coil in each of said circuits, of two repeating elements together comprising a common input electrode, an anode for each element, and two cathodes, said input electrode being connected to an 55 intermediate point in the secondary winding of the input repeating coil, the primary winding of said output repeating coil being divided, the two divisions being connected respectively between the cathode and anode 60 of the two repeating elements.

In witness whereof, I hereunto subscribe my name this 25th day of October A. D., 1916.

ALEXANDER MCLEAN NICOLSON.
